Carl F. Wolters, Kenmore, and Allan H. Tober,
Buffalo, N. Y., assignors to Remington Rand
Inc., Buffalo, N. Y.

Application May 4, 1939, Serial No. 84,799

Term of patent 7 years

To all whom it may concern:

Be it known that we, Carl F. Wolters and Allan H. Tober, citizens of the United States, residing at Kenmore and Buffalo, respectively, in the county of Erie and State of New York, have invented a new, original, and ornamental Design for a Combined Photographic Printer and Holder Therefor, of which the following is a specification, reference being had to the accompanying drawing, forming part thereof.

Figure 1 is a perspective of a combined photo-

tographic printer and holder therefor, showing our new design.

Figure 2 is an end elevation showing the opposite end of the combined photographic printer and holder therefor, from that shown in Figure 1.

We claim:

The ornamental design for a combined photographic printer and holder therefor, as shown.

CARL F. WOLTERS.
